Adding Machine Co., Chicago, Ill., a corpora-
tion of Illinois

Application May 19, 1951, Serial No. 15,250

Term of patent 14 years

(Cl. D33—14)

To all whom it may concern:

Be it known that I, Carl Buehler, a citizen of the United States, residing at Palatine, in the county of Cook and State of Illinois, have invented a new, original, and ornamental Design for a Combined Drafting Board, Reference Table, and Cabinet, of which the following is a specification, reference being had to the accompanying drawing, forming part thereof.

Fig. 1 is a perspective view of a combined drafting board, reference table, and cabinet, showing my new design;

Fig. 2 is a front elevational view thereof; and Fig. 3 is a right side elevational view thereof. The rear of the cabinet portion is plain.

I claim:

The ornamental design for a combined drafting board, reference table, and cabinet, substantially as shown and described.

CARL BUEHLER.
